MANUFACTURE OF BAGS

Russell J. Williams, Clayton, and Milton J. Heimos, Lemay, Mo., assignors to Bemis Bro. Bag Company, St. Louis, Mo., a corporation of Missouri

Application April 5, 1954, Serial No. 420,958

7 Claims. (Cl. 93—8)

This invention relates to the manufacture of bags, and more particularly to apparatus for and methods of manufacturing a continuous multi-ply web having patches between the plies thereof spaced at intervals along the length of the web, and adapted to be formed into bags.

The manufacture of several different types of multi-ply paper bags involves the insertion of patches between the plies. One such type of bag is a window bag having a patch of open-mesh fabric in the window, such as is shown in Fig. 11 of U. S. Patent 2,428,266. Among the several objects of this invention may be noted the provision of an improved and simplified apparatus for and method of manufacturing a continuous multi-ply web having patches between the plies thereof, and spaced at bag length intervals along the length of the web, the web being adapted to be formed into bags by conventional bag-forming methods involving tubing, segmenting and bottoming; the provision of an apparatus and method of the class described which, while eliminating certain machine elements and method steps heretofore used, reliably accomplish insertion of the patches in a continuous operation, and the provision of an apparatus and method of the class described which may be readily utilized for the insertion of patches of different lengths in the longitudinal direction of the web. Other objects and features will be in part apparent and in part pointed out hereinafter.

The invention accordingly comprises the constructions and methods hereinafter described, the scope of the invention being indicated in the following claims.

In the accompanying drawings, in which one of various possible embodiments of the invention is illustrated,

Fig. 1 is a view in transverse elevation of part of a bag machine equipped with apparatus of this invention, parts being broken away;

Fig. 2 is a vertical cross section taken on line 2—2 of Fig. 1;

Fig. 3 is a fragment of Fig. 2 with certain details omitted illustrating a moved position of parts;

Figs. 4 and 5 are vertical cross sections taken on lines 4—4 and 5—5, respectively, of Fig. 1; and

Figs. 6 and 7 are cross sections taken on lines 6—6 and 7—7, respectively, of Fig. 4.

Corresponding reference characters indicate corresponding parts throughout the several views of the drawings.

Referring to the drawings, reference characters 1 and 2 designate the side frames of a conventional bag machine having an apparatus of this invention installed therein. These are braced by a cross-channel 3. A cross-shaft of the bag machine is indicated at 4. At 5 is shown a combining guide. This consists of a roll, journalled at its ends in bearings 7. These bearings are mounted on inclined faces 8 of the side frames, as by means of screws 9 extending through slots 10 in the bearings, and may be adjusted on the faces 8 (screws 9 being loosened) to vary the position of the roll. Webs W-1 and W-2 supplied from web rolls (not shown) are guided for travel

2

toward the combining roll 5 in spaced apart paths with the webs converging at the combining roll to form a two-ply web W, the latter travelling on through the bag machine wherein it is formed into bags in conventional manner involving tubing, segmenting and bottoming, as will be understood in the art. The web W-1 is shown as travelling around a guide roll 11 and thence in a reach R-1 inclined rearward and downward to the combining roll, and the web W-2 is shown as travelling around guide rolls 12 and 13 and thence in a reach R-2 inclined forward and downward to the combining roll. The bite of webs W-1 and W-2, i. e., the transverse line on which they come into engagement, is indicated at B.

Reference character 15 generally designates a patch cutter unit for severing patches from a web W-3 of patch material, such as paper, or open-mesh fabric, supplied from a web roll (not shown). As shown, the patch cutter unit is mounted on a pair of bars 17 and 19 which extend between the side frames 1 and 2 in the space between the ply-forming webs W-1 and W-2, where they converge toward the combining roll. It comprises a pair of side frames 21 and 23 tied together by a cross-girt 25. Each of side frames 21 and 23 has a notch 27 at its forward lower corner receiving bar 17 and a notch 29 at its rearward lower corner receiving bar 19. The side frames 21 and 23 are fixed on the bars 17 and 19 by clamp members 31 engaging the bottoms of bars 17 and 19, clamp screws 33 extending through holes in the members 31 and being threaded in the side frames 21 and 23.

The patch cutter unit includes means for feeding the patch-forming web W-3 into the bite B of the ply-forming webs W-1 and W-2. As shown, this means comprises a pair of draw rolls 35 and 37 extending between the side frames 21 and 23. Roll 35 is journalled at its ends in bearings 39 located at the inner ends of slots 41 in side frames 21 and 23. Roll 37 is journalled at its ends in bearings 43 slidable in the slots 41. Roll 37 is biased away from roll 35 by springs 45 reacting from bearings 39 against bearings 43. Caps 47 close the open ends of the slots. These caps are slidable on screws 49 and are biased against the edges of the side frames by springs 51. A shaft 53 extends through bearings 55 slidable in the slots between the bearings 43 and the caps. Screws 57 threaded in the caps limit the outward movement of the bearings 55. Fixed on the shaft 53 are eccentrics 59 engageable with the bearings 43. Shaft 53 has a handle 61 outward of side frame 21 and is rotatable 180°, as determined by engagement of a pin 63 extending radially from the shaft with a pair of stops 65 on the side frame 21, for rotating the eccentrics from a draw roll closing position wherein the rolls may grip web W-3 therebetween to a draw roll releasing position allowing roll 37 to separate from roll 35 for web-threading purposes. The pass plane of the draw rolls is located between the planes of the convergent reaches R-1 and R-2 of webs W-1 and W-2 and substantially tangent to the combining roll, at the bite B of the webs W-1 and W-2.

The patch-forming web W-3 being fed forward by the draw rolls 35 and 37 into the bite B of webs W-1 and W-2 travels between a hardened anvil roll 67 and a rotary knife roll 69 carrying a knife 71. The anvil roll is mounted on a drive shaft 73 journalled in bearings 75, mounted in the side frames 21 and 23. The knife roll is journalled at its ends in bearings 77 slidable in slots 79 in the side frames. The knife roll is biased away from the anvil roll by springs 81 reacting from the inner ends of the slots 79 against the bearings 77, its position being determined by the engagement of bearings 77 with screws 83 threaded in caps 85 for the open ends of the slots 79. The anvil roll is substantially tangent to the pass plane of the draw rolls.

Webs W-1 and W-2 are fed forward at bag machine

speed. Draw rolls 35 and 37 are driven to feed the patch-forming web W-3 at a speed lower than the speed of webs W-1 and W-2, and the anvil roll 67 and knife roll 69 are driven at a speed so related to the speed of the draw rolls as to cut patches of the desired size. The drive for these elements is taken off a shaft 87 of the bag machine via a train of gears including a gear 89 on shaft 87, an idler gear 91 journalled in a bearing bracket 93, and a gear 95 on the anvil roll shaft 73, the latter extending beyond side frame 2 and being journalled in an outboard bearing bracket 97. A gear 99 on the anvil roll shaft 73 outward of side frame 23 meshes with a gear 101 on the knife roll. Draw roll 35 is driven from the anvil roll shaft 73 via a change gear 103 on shaft 73 outward of side frame 21, an idler gear 105 carried by a pivoted sector 107, and a gear 109 on the roll 35. A gear 111 on the roll 35 outward of the side frame 23 meshes with a gear 113 on draw roll 37 to drive the latter. At 115 is shown a gear in mesh with a gear 117 on shaft 87 for driving the latter.

Operation is as follows:

Draw rolls 35 and 37 are continuously driven to feed the patch-forming web W-3 at a speed lower than the speed of ply-forming webs W-1 and W-2 appropriate to the desired spacing for the patches along the length of the composite web W. It will be understood that the lower the speed of the web W-3, in relation to the speed of webs W-1 and W-2, the greater the spacing of the patches, and vice versa. Different draw roll speeds may be obtained by changing gears at 103. Web W-3 is fed between the anvil roll 67 and the knife roll 69, which are driven at a speed so related to the speed of web W-3 as to cut a patch P (see Fig. 3) of the desired length upon each revolution of the knife roll. The rolls 35, 37, 67 and 69 rotate in the directions indicated by the directional arrows in Figs. 2 and 3. The distance from the transverse cut line C where the knife 71 on the knife roll cuts the web W-3 against the anvil 67 is spaced from the bite B of the ply-forming webs W-1 and W-2 a distance corresponding generally to the length of the cut patches. This distance may be set by adjustment of the combining roll 5. It need not be exactly the length of a patch.

The knife roll is timed to cut the web W-3 substantially at the instant that the end of the web W-3, as fed forward by the draw rolls, is caught in the bite B of the ply-forming webs W-1 and W-2 (see Fig. 3). The patch, immediately upon being cut, and having its forward end caught in the bite of webs W-1 and W-2, is drawn in between webs W-1 and W-2 at the speed of webs W-1 and W-2. Since web W-3 is fed at a speed lower than the speed of webs W-1 and W-2, the patch is pulled away from the freshly cut end of web W-3, and thus becomes spaced from the next patch to be cut. When the patch P is cut and drawn in between the webs W-1 and W-2, web W-3 continues to feed forward between the anvil roll and the knife roll toward the bite B (see Fig. 2), and when the knife roll completes a revolution from the cutting position shown in Fig. 3, another patch is cut, and so on.

In view of the above, it will be seen that the several objects of the invention are achieved and other advantageous results attained.

As various changes could be made in the above constructions and methods without departing from the scope of the invention, it is intended that all matter contained in the above description or shown in the accompanying drawings shall be interpreted as illustrative and not in a limiting sense.

We claim:

1. Apparatus for forming a continuous multi-ply web having patches between the plies thereof with the patches spaced at intervals along the length of the web, comprising a combining guide, means for guiding a plurality of continuous ply-forming webs for travel at a predeter-

mined speed toward the combining guide in spaced paths with the webs converging together to meet at the combining guide, a cutter located in the space between the ply-forming webs where they converge toward the combining guide, and means for continuously feeding a patch-forming web at a speed lower than the speed of said ply-forming webs past the cutter and into the bite of said ply-forming webs where they meet at said guide, said cutter being positioned for travel of the patch-forming web in a substantially straight-line path from the cutter to the combining guide and into the bite of said ply-forming webs, said cutter being so located relative to the combining guide as to cut off the patch-forming web on a transverse cutting line spaced from the bite of said ply-forming webs a distance measured along said straight-line path corresponding generally to the desired patch length, and means for operating said cutter and timing the operation thereof to cut the patch-forming web to form a patch substantially at the instant that the end 15 of said patch as cut from the patch-forming web is caught in the bite of said ply-forming webs, whereby the patch immediately upon being cut is drawn in between the ply-forming webs at the speed of the ply-forming webs, and is pulled away from the freshly cut end of the patch-forming web.

2. Apparatus for forming a continuous multi-ply web having patches between the plies thereof with the patches spaced at intervals along the length of the web, comprising a combining guide, means for guiding a plurality of continuous ply-forming webs for travel at a predetermined speed toward the combining guide in spaced paths with the webs converging together to meet at the combining guide, a cutter including a rotary knife located in the space between the ply-forming webs where they converge toward the combining guide, means for continuously feeding a patch-forming web at a speed lower than the speed of said ply-forming webs past the cutter and into the bite of said ply-forming webs where they meet at said guide, said feeding means and said cutter being so positioned relative to one another and to the combining guide that the patch-forming web travels in a substantially straight-line path from the feeding means past the cutter to the combining guide and into the bite of said ply-forming webs, said cutter being located relative to the combining guide for cutting off the patch-forming web on a transverse cutting line spaced from the bite of said ply-forming webs a distance measured along said straight-line path corresponding generally to the desired patch length, and means for rotating the knife and timing the operation thereof to cut the patch-forming web to form a patch substantially at the instant that the end of said patch as cut from the patch-forming web is caught in the bite of said ply-forming webs, whereby the patch immediately upon being cut is drawn in between the ply-forming webs at the speed of the ply-forming webs, and is pulled away from the freshly cut end of the patch-forming web.

3. Apparatus for forming a continuous multi-ply web having patches between the plies thereof with the patches spaced at intervals along the length of the web, comprising a combining roll, means for guiding a plurality of continuous ply-forming webs for travel at a predetermined speed toward the combining roll in spaced paths with the webs converging together to meet at the combining roll, a cutter comprising a rotary anvil and a rotary knife located in the space between the ply-forming webs where they converge toward the combining roll, a pair of draw rolls for feeding a patch-forming web at a speed lower than the speed of said ply-forming webs 60 between the anvil and knife into the bite of said ply-forming webs where they meet at said combining roll, the pass plane of said draw rolls and cutter being substantially tangent to the combining roll at the bite of said ply-forming webs, said knife being located to cut off the patch-forming web on a transverse cutting line spaced 65 between the anvil and knife into the bite of said ply-forming webs where they meet at said combining roll, the pass plane of said draw rolls and cutter being substantially tangent to the combining roll at the bite of said ply-forming webs, said knife being located to cut off the patch-forming web on a transverse cutting line spaced 70 between the anvil and knife into the bite of said ply-forming webs where they meet at said combining roll, the pass plane of said draw rolls and cutter being substantially tangent to the combining roll at the bite of said ply-forming webs, said knife being located to cut off the patch-forming web on a transverse cutting line spaced 75 between the anvil and knife into the bite of said ply-forming webs where they meet at said combining roll, the pass plane of said draw rolls and cutter being substantially tangent to the combining roll at the bite of said ply-forming webs, said knife being located to cut off the patch-forming web on a transverse cutting line spaced

from the bite of said ply-forming webs a distance corresponding generally to the desired patch length, and being operable to cut the patch-forming web to form a patch substantially at the instant that the end of the patch-forming web is caught in the bite of said ply-forming webs, whereby the patch immediately upon being cut is drawn in between the ply-forming webs at the speed of the ply-forming webs, and is pulled away from the freshly cut end of the patch-forming web.

4. Apparatus for forming a continuous multi-ply web having patches between the plies thereof with the patches spaced at intervals along the length of the web, comprising a combining roll, guide rolls for guiding two continuous ply-forming webs for travel at a predetermined speed toward the combining roll in convergent reaches meeting at the combining roll, a cutter comprising a rotary anvil and a rotary knife located in the space between the ply-forming webs where they converge toward the combining roll, a pair of draw rolls for feeding a patch-forming web at a speed lower than the speed of said ply-forming webs between the anvil and knife into the bite of said ply-forming webs where they meet at said combining roll, the pass plane of said draw rolls and cutter being substantially tangent to the combining roll at the bite of said ply-forming webs, said knife being located to cut off the patch-forming web on a transverse cutting line spaced from the bite of said ply-forming webs a distance corresponding generally to the desired patch length, and being operable to cut the patch-forming web to form a patch substantially at the instant that the end of the patch-forming web is caught in the bite of said ply-forming webs, whereby the patch immediately upon being cut is drawn in between the ply-forming webs at the speed of the ply-forming webs, and is pulled away from the freshly cut end of the patch-forming web.

5. Apparatus as set forth in claim 4 wherein the combining roll and cutter are relatively adjustable to increase or decrease the spacing of said transverse cutting line and the bite of said ply-forming webs.

6. The method of forming a continuous multi-ply web having patches between the plies thereof with the patches spaced at intervals along the length of the web, comprising the steps of feeding a plurality of continuous ply-forming webs at a predetermined speed toward a combining guide in spaced paths with the webs converging together as they approach the guide and meeting at the guide, continuously feeding a continuous patch-forming web in a substantially straight-line path into the bite of

the ply-forming webs at the combining guide at a speed lower than the speed of said ply-forming webs, and cutting the patch-forming web on a line extending transversely across said straight-line path and spaced from the bite of the ply-forming webs a distance measured along said straight-line path corresponding generally to the desired patch length to form a patch substantially at the instant that the end of said patch as cut from the patch-forming web is caught in the bite of said ply-forming webs, whereby the patch immediately upon being cut is drawn in between the ply-forming webs at the speed of the ply-forming webs, and is pulled away from the freshly cut end of the patch-forming web.

7. Apparatus for forming a continuous multi-ply web having patches between the plies thereof with the patches spaced at intervals along the length of the web, comprising a combining guide, means for guiding a plurality of continuous ply-forming webs for travel at a predetermined speed toward the combining guide in spaced paths with the webs converging together to meet at the combining guide, a cutter comprising an anvil and a rotary knife located in the space between the ply-forming webs where they converge toward the combining guide, a pair of draw rolls for feeding a patch-forming web at a speed lower than the speed of said ply-forming webs between the anvil and knife into the bite of said ply-forming webs where they meet at said combining guide, the pass plane of said draw rolls and cutter being substantially tangent to the combining guide at the bite of said ply-forming webs, said knife being located to cut off the patch-forming web on a transverse cutting line spaced from the bite of said ply-forming webs a distance corresponding generally to the desired patch length, and being operable to cut the patch-forming web to form a patch substantially at the instant that the end of the patch-forming web is caught in the bite of said ply-forming webs, whereby the patch immediately upon being cut is drawn in between the ply-forming webs at the speed of the ply-forming webs, and is pulled away from the freshly cut end of the patch-forming web.
